UNITED STATES PATENT OFFICE.

JOSEF REULEAUX, OF WILKINSBURG, PENNSYLVANIA, ASSIGNOR TO
ALEXANDER LAUGHLIN, OF SEWICKLEY, PENNSYLVANIA.

GAS-PRODUCER.

SPECIFICATION forming part of Letters Patent No. 758,475, dated April 26, 1904.

Application filed June 2, 1903. Serial No. 159,767. (No model.)

To all whom it may concern:

Be it known that I, JOSEF REULEAUX, of Wilkinsburg, in the county of Allegheny and State of Pennsylvania, have invented certain new and useful Improvements in Gas-Producers; and I do hereby declare the following to be a full, clear, and exact description of the invention, such as will enable others skilled in the art to which it appertains to make and use the same.

The objects of this invention are, first, to provide for the gradual and uniform feeding of fuel to a gas-producer; secondly, to avoid feeding in excess of the actual discharge of the fuel into the producer; third, to provide for an even distribution of the fuel onto the fire-bed; fourth, to control the deposit of the fuel at any one point, and, lastly, to provide a mechanical feeder which while attaining the ends above outlined will effectively guard against the undue loss of gas during the charging operations and will be simple, inexpensive, and positive in operation.

The invention will be hereinafter fully set forth, and particularly pointed out in the claims.

In the accompanying drawings, Figure 1 is a vertical sectional view of a gas-producer equipped with my improvements. Fig. 2 is a section on line 2 2, Fig. 1. Fig. 3 is a horizontal section on line 3 3, Fig. 1. Fig. 4 shows in section the application of a portion of my improvements to a producer having the ordinary bell-valve over its charging-opening.

Referring to the drawings, 1 designates a gas-producer, and 2 the charging-opening formed in the top thereof. On this top, above the opening, is a casing 3, having at its center a cylindrical portion wherein is rotatably mounted the upper cylindrical end of a discharge-spout 4. That portion of the discharge-spout extending below the casing and through the charging-opening is set at an angle to its axis, so that the fuel may be discharged toward any one point or uniformly onto the fire-bed by gradually rotating the spout as the fuel is passing therethrough. It is obvious that any suitable means may be employed for readily effecting this rotation,

since the spout moves entirely independently 50 of the casing, which latter is stationary. The means shown embraces a sectional shaft 5, extended upwardly through the top of the casing 3 and having a beveled pinion 6 in mesh with the pinion of a driving-shaft 7. 55

8 is the coal hopper or reservoir, the outlet from which is controlled by a cylindrical valve 9, fast on shaft 7. This valve fits within the cylindrical or bulged portion of a casing 10 and at its ends is flush with and suitably packed against lateral flanges 12 concentric with the bulged portion. This permits the valve to be readily inserted into and removed from the casing. The latter at its lower end opens into what I term a "fuel-receiving" chamber 13, forming communication between the hopper-connecting casing 10 and the discharge-casing 3, being set at right angles to them both—that is to say, the coal-receiving chamber 13 occupies a horizontal 70 position, while the casings 10 and 3 are perpendicular. Thus the connecting-casing 10 is out of line with charging-opening.

In the rotation of shaft 7 valve 9 will take a certain amount of coal in its pocket and 75 discharge it through casing 10 into chamber 13, at the same time preventing the escape of gas into the hopper. The coal falling into chamber 13 is forced therefrom by a rotary pusher 14, located in the outer end of such 80 chamber out of line with the discharge from the hopper. This pusher is shown in the form of an obliquely-set disk mounted on the inner end of a shaft 15, belted or geared to shaft 7. The rotation of the obliquely-set 85 disk serves to gradually force the coal from chamber 13 into the discharge-spout, and by the latter it will be evenly distributed over the fire-bed. If, however, it be desired to deposit an extra amount of fuel at a given point, 90 it is only necessary to uncouple shaft 5, so as to prevent the rotation thereof when the discharge-spout is in the desired position. By reason of the peculiar formation of the pusher no coal can possibly fall in rear thereof, its 95 forwardly-projected edge not at any time intersecting the plane of the discharge from the hopper.

If the coal is not being discharged from chamber 13 as rapidly as it is fed from the hopper, there is no danger of damage from an over-supply, for the reason that the coal within the 5 casing between the receiving-chamber and the valve will prevent the coal contained in the pocket of the latter from falling therefrom, so that although the valve continues to revolve the coal will remain confined in the valve until the quantity within the receiving-chamber 10 has been lessened.

In Fig. 4 I have shown the application of my feeder to a producer having the ordinary bell-valve 16 for closing the lower end of the casing 17, such valve being actuated by the movements of a weighted lever 18. In this form the rotary spout is not employed.

From what has been said it will be seen that by means of my invention fuel may be readily 20 and uniformly supplied to a gas-producer without danger from overfeeding from the hopper and that the discharge of the fuel into the producer will be easily and gradually effected, while the quantity supplied at any one point 25 may be readily controlled or an even distribution secured. It is obvious also that by mounting the feeding-valve in an open-end casing it may be readily removed for the purpose of repairs, &c., and that when it is desired 30 to retain the discharge-spout in any one position it is only necessary to uncouple the operating-shaft thereof.

I claim as my invention—

1. In a gas-producer having a charging-opening and a casing thereover, a fuel-reservoir out of line with such casing, a horizontally-disposed fuel-receiving chamber opening into said casing, a second casing connecting said chamber to said reservoir, an obliquely-arranged disk positioned within said chamber to one side of the plane of the opening of said second casing into said receiving-chamber, and means for rotating the disk, as set forth.

2. In a gas-producer having a charging-opening and a casing thereover, a fuel-reservoir out of line with such casing, a horizontally-disposed fuel-receiving chamber opening into said casing, a second casing connecting said chamber to said reservoir, a valve in such second casing for supplying fuel from the hopper to said chamber, an obliquely-arranged disk positioned within said chamber to one side of the plane of the opening of said second casing into said receiving-chamber, and means for 55 rotating the disk, as set forth.

3. In a gas-producer having a charging-opening and a casing thereover, a fuel-reservoir out of line with such casing, a horizontally-disposed fuel-receiving chamber opening 60 into said casing, a second casing connecting said chamber to said reservoir, a valve in such second casing for periodically supplying fuel from the hopper to said chamber, an obliquely-arranged disk positioned within said chamber to one side of the plane of the opening of said 65

second casing into said receiving-chamber, and a rotary shaft for said disk extended outwardly through one end of the chamber, as set forth.

4. In a gas-producer having a charging-opening and a casing thereover, a fuel-reservoir out of line with such casing, a horizontally-disposed fuel-receiving chamber opening into said casing, a second casing connecting said chamber to said reservoir, a rotary valve in such second casing for supplying fuel from the hopper to said chamber, a rotary obliquely-set disk within said chamber, and actuating means connecting said valve and disk, as set forth.

5. In a gas-producer having a charging-opening and a casing thereover, a fuel-reservoir out of line with such casing, a horizontally-disposed fuel-receiving chamber opening into said casing, a second casing connecting said chamber to said reservoir, a rotary valve for intermittently supplying fuel from the hopper to the receiving-chamber, a shaft for such valve, a rotary obliquely-set disk within such receiving-chamber, a shaft for such disk, and a connection between such shafts, as set forth.

6. In a gas-producer having a charging-opening and a casing thereover, a fuel-reservoir out of line with such casing, a horizontally-disposed fuel-receiving chamber opening into said casing, a second casing connecting said chamber to said reservoir, a valve in such second casing for supplying fuel from the hopper to said chamber, a shaft therefor, an obliquely-arranged disk positioned within said chamber to one side of the plane of the opening of said second casing into said receiving-chamber, a rotary shaft for said disk extended outwardly through one end of the chamber, and actuating means connecting the shafts of the valve and pusher, as set forth.

7. In a gas-producer having a charging-opening and a stationary casing thereover having a central opening, a fuel-discharge spout mounted in said central opening and extended diagonally through said charging-opening, a sectional shaft connected to said spout, and means for actuating such shaft, as set forth.

8. In a gas-producer having a charging-opening at the center of its top, a casing mounted on said top having a central opening, a fuel-chamber opening into said casing at right angles to said central opening, means for forcing fuel from said chamber, a spout having its upper portion fitted in said central opening, the lower portion of said spout being extended obliquely through the opening in the top of the producer, and means for rotating said spout, as set forth.

9. In a gas-producer having a charging-opening, and a casing thereover, in combination, a fuel-reservoir out of line with such opening, a fuel-receiving chamber forming a right-angular communication between the reservoir and said casing, a rotary valve for 130

feeding fuel from the reservoir to said chamber, a shaft therefor, a rotary pusher within the chamber, a shaft therefor, a connection between said shafts, a rotary discharge-spout
5 extended through the charging-opening, and a shaft connected thereto and geared to the shaft of the rotary valve, as set forth.

In testimony whereof I have signed this specification in the presence of two subscribing witnesses.

JOSEF REULEAUX.
